UNITED STATES PATENT OFFICE

CHARLES S. THOMPSON, OF PARK RIDGE, AND WILLIAM B. LONG, OF CHICAGO, ILLINOIS, ASSIGNORS TO UNION SPECIAL MACHINE COMPANY, OF CHICAGO, ILLINOIS, A CORPORATION OF ILLINOIS

SEWING MACHINE

Application filed April 8, 1927. Serial No. 182,074.

The invention relates to new and useful improvements in sewing machines, and more particularly to a sewing machine wherein the actuating parts for the needle, looper and feed are enclosed within the frame of the machine.

An object of the invention is to provide a machine of the above type having a hollow base supporting a hollow standard with which it communicates, which in turn supports a hollow overhanging arm with which it communicates, wherein the main shaft is disposed in the hollow base and provided with actuating members which are adapted to contact with a quantity of oil in the hollow base for splashing the same and throwing the oil on to the actuated parts for lubricating the same.

A further object of the invention is to provide a machine of the above type wherein said hollow base has a vertical partition for separating the feed bar and the looper from the actuating parts in the oil reservoir.

A still further object of the invention is to provide a machine of the above type wherein the partition is provided with an opening of sufficient size to permit a link to connect the looper with the actuating parts within the hollow portion of the frame containing the oil, and closing said opening by a yielding member which permits the link to move back and forth and laterally as it oscillates the looper.

A still further object of the invention is to provide a machine of the above type wherein the eccentric for moving the feed bar back and forth is located within the chamber of the hollow base containing the feed bar and is lubricated through contact with an oiling pad.

A still further object of the invention is to provide a machine of the above type wherein the feed dog is raised and lowered by the eccentric on the actuating shaft, and a presser bar for supporting the presser foot is located directly above said eccentric.

A still further object of the invention is to provide a machine of the above type wherein the lever for reciprocating the needle bar is mounted on a supporting shaft located in

the hollow standard, and said lever is located entirely within said hollow standard and hollow overhanging arm, and an actuating strap for the needle lever is also located within said hollow standard.

These and other objects will in part be obvious and will in part be hereinafter more fully disclosed.

In the drawings—

Figure 1 is a front view of the machine embodying the improvements with certain of the parts broken away and sectioned to show certain of the actuating parts;

Fig. 2 is an end view of the machine with certain of the parts broken away;

Fig. 3 is a view from the rear of the machine with the cover plate for the feed rocker removed and the detachable sections of the frame removed to expose the actuating parts within said hollow base, hollow standard and hollow arm;

Fig. 4 is a sectional view through the overhanging arm and standard at a point below the needle lever and showing the inclined floor trough for draining the oil back into the standard;

Fig. 5 is a section through the hollow standard a short distance above the cloth plate, with the cover plate for the feed rocker, also the cover plate for the looper and the feeding mechanism removed;

Fig. 6 is a sectional view transversely through the machine on the line 6—6 of Fig. 1;

Fig. 7 is a sectional view lengthwise of the work support, and showing the actuating link for the looper, and the manner of passing the same through a partition;

Fig. 8 is a detail in section and showing in side view the operating eccentric strap for the feed rocker;

Fig. 9 is a transverse sectional view through the machine, showing the means for giving the looper a needle avoiding movement;

Fig. 10 is a detail in section showing the manner of supporting the flexible member which closes the opening through which the actuating link of the looper works;

Fig. 11 is a bottom plan view of the cover plate for the feed rocker, and

Fig. 12 is a sectional view on the line 12, 12 of Fig. 11.

- 5 The invention is directed to a sewing machine of the enclosed type; that is, a sewing machine wherein the actuating parts for the feed dog, the needle and the looper are all enclosed within the frame of the machine.
- 10 Said frame includes a hollow base having an integral hollow standard, which in turn has an integral hollow overhanging arm, wherein the base, standard and arm all communicate, and the hollow base forms an enclosed chamber, which serves as a reservoir for the lubricating oil. There is a dividing partition extending transversely across the hollow base which separates the feed bar and looper from the actuating parts and the oil reservoir in
- 15 which the actuating parts operate. The main shaft is located in the base and beneath the cloth plate, and of course, extends through said partition to the forward end of the machine. At the forward end of the hollow arm
- 20 is a needle head in which a needle bar reciprocates. The lever for reciprocating the needle bar is located in the hollow arm and the shaft on which the lever is mounted extends transversely across the upper end of the standard, so that all of the bearings for the lever are
- 25 within the standard. The lever is reciprocated by an eccentric strap located within said hollow standard, and cooperating with an eccentric on the main shaft. Located
- 30 alongside of said eccentric is a counterbalancing member. The looper which cooperates with the needle is located in the hollow base, but in front of the cross partition, so that it is in a part of the base which is separated from the oil reservoir. The looper is
- 35 mounted on a looper carrier which is supported by a shaft that is oscillated for giving the looper a needle avoiding movement. This shaft extends through the transverse
- 40 partition, and is provided with an arm carrying a ball stud with which the eccentric strap cooperates. This eccentric strap in turn cooperates with an eccentric on the main shaft in the oil reservoir. The looper carrier is oscillated on its support by a link which passes
- 45 through an enlarged opening in the partition, so that the link can move endwise and laterally. A flexible member is provided for preventing the oil from splashing through said
- 50 opening. This link is in turn actuated by a rock shaft mounted in the hollow base and the rock shaft is actuated by an eccentric strap cooperating with an eccentric on the main shaft. As the main shaft rotates, these
- 55 eccentric members running in a quantity of oil will cause the splashing of the oil, and the throwing of a mist of oil up through the hollow standard and out into the hollow arm.
- 60 The feed dog is mounted on a feed bar attached to a feed rocker at the rear side of the

hollow base. Said rocker is oscillated by an eccentric strap cooperating with the eccentric on the main shaft, which eccentric and strap are located in the hollow base on the opposite side of the partition from the oil reservoir. The feed dog is raised and lowered by the eccentric on the main shaft.

70 Referring more in detail to the drawings, the invention resides in a sewing machine consisting of a hollow frame. This hollow frame is provided with a base 1 which has a cloth plate 2 at its upper face. The base is enclosed and is provided with a cross partition 3 forming a chamber 4 adapted to contain a lubricating oil.

75 Mounted on the base is a hollow standard 5 which is preferably formed integral with the base portion. Carried by the hollow standard is a hollow overhanging arm 6 which is also preferably formed integral with the standard. At the outer end of the overhanging arm is a needle head 7.

80 Mounted in the needle head is a needle bar 8 carrying a needle 9. The needle bar is reciprocated in the head by means of a lever 10 which is fulcrumed so as to swing about the pivotal axis indicated at 11. The lever is mounted within the hollow arm and extends into the upper end of the hollow standard. The lever is vibrated on its pivotal support 90 for reciprocating the needle by a pitman or eccentric strap 12 which is pivoted at 13 to the needle lever. This strap cooperates with an eccentric 14 mounted on the main shaft 15.

95 The main shaft 15 is mounted in suitable bearings carried by the hollow base. The shaft extends all the way across the base, from one end thereof to the other, and projects through the wall of the base where it is provided with a driving pulley 16. The shaft is 100 located a short distance above the bottom of the hollow base, and the portion of the hollow base in which the eccentric 14 is located, is as noted above, adapted to hold a quantity 105 of lubricating oil, so that as the eccentric 110 rotates, it will cause the oil to be splashed and thrown up into the hollow standard. On the pitman 12 is a plate 17 which is, in a measure, a splash plate. The plate has its outer edges curved downwardly so as to deflect oil 115 thrown against it back into the reservoir in the hollow base beneath the hollow standard. The splashing of the oil, however, into the hollow standard, will cause quite a quantity 120 of the oil to rise in mist form and thoroughly lubricate the bearings for supporting the needle lever, the bearings connecting the actuating pitman to the needle lever, and the bearings for the needle bar 8. A felt pad 18 125 is provided in the needle head and is disposed so as to surround the needle bar. This pad becomes saturated with oil and aids in lubricating the needle bar. Adjacent the pad 18 is a pad 19 which extends part way across the 130 needle head and, in a measure, divides the

lower part of the needle head, which is also hollow, from the hollow arm. Leading from a point adjacent the pad 19 along the floor of the overhanging arm is an inclined trough 20. This inclined trough extends down the inner wall of the standard and serves as a means for draining the oil accumulating at the bottom of the overhanging arm back through the standard into the reservoir.

10 The machine at the rear thereof is provided with a detachable cover plate 21. The casing is divided along the lines *a*, *b*, *c* and *d*, to provide a removable section. This removable section extends clear to the needle head and covers the rear part of the needle head. When this part of the casing is removed, it exposes the needle lever and the actuating parts therefor; also the parts of the needle bar and presser bar within the 20 needle head.

Cooperating with the needle beneath the work support is a looper 22. The looper is mounted on a looper carrier 23 which is pivoted at 24 to a looper support 25. The shaft 25 carrying the looper support 25 extends through the partition 3 into the oil reservoir. The shaft is indicated at 29 in Fig. 9. On the inner end of the shaft is an arm 30. An eccentric strap 31 is connected to a ball stud 32 on this arm 30, and said eccentric strap cooperates with the eccentric 33 on the main shaft 15. This serves to oscillate the looper support, and gives to the looper a needle avoiding movement. It will be noted that 35 these actuating parts for the shaft 29 dip into the oil and are thoroughly splashed and lubricated thereby.

The looper is oscillated for moving it into and out of the needle thread loop by means of 40 a link 34. The link 34 extends through an opening 35 in the partition 3 (see Fig. 7). At its inner end, the link is connected to a rock frame 36. Said rock frame 36 is mounted to oscillate about a vertical axis (see Fig. 45). An arm 37 of the rock frame carries a ball stud 38 to which the link is connected. The arm 39 of the rock frame carries a ball stud 40 to which an eccentric strap 41 is connected. This eccentric strap 41 cooperates 50 with an eccentric 42 on the main shaft 15. This eccentric dips into the oil in the reservoir and together with the other rotating parts on the main shaft, splashes the oil, so that the rock frame and the parts connected thereto are all thoroughly lubricated. The link 34 as it is moved endwise will have a slight lateral movement. The opening 35 in the partition is sufficiently large to permit this lateral as well as endwise movement of 60 the link. In order to prevent the oil from being carried through into the chamber of the hollow base where the looper is located, we have provided a rubber diaphragm 43. This rubber diaphragm has an opening there- 65 through which fits closely to the link 34. The

rubber diaphragm is held by a supporting bracket 44 secured by screws to the partition. This bracket is of metal, and the opening through the bracket is sufficiently large to permit the ink to have its free lateral movement. The rubber diaphragm permits the link to move laterally, but at the same time, closes the opening through the partition. Any suitable yielding or elastic member may be used for this purpose.

The partition 3 as noted above, forms a chamber for the looper, which is separated from the oil reservoir, so that the oil is not sprayed on to the looper. The fabric is moved across the work support by the feed dog 45. This feed dog is carried by a feed bar 46 which is located in the chamber with the looper 22, so that it is free from the splashing oil in the oil reservoir. The feed bar 46 is pivoted at 47 to a feed rocker which in turn is pivoted at 48. This feed rocker is oscillated by means of an eccentric strap 49 which cooperates with an eccentric 50 on the main shaft 15. The eccentric strap is pivoted to a stud or bolt 51 which is adjustable in a slot 52 in the feed rocker. This enables the feed stroke to be varied. The eccentric is located on the main shaft in the same chamber as the looper and the feed dog, and therefore, it is not subjected to the splashing oil in the oil reservoir. The feed rocker and the rear portion of the feed bar are covered by the removable cover plate 21. This removable cover plate carries an oiling pad 54. The oiling pad is secured to the cover plate by means of a suitable screw 55. This oiling pad is disposed so that when saturated with oil, it will cause oil to drip or to pass through the opening 56 in the eccentric strap cooperating with the eccentric 50. A tube 57 extends through the upper wall of the cover plate and leads into this oiling pad 54. By this means, oil can be readily supplied to the oiling pad 54. The cover plate is held on the supporting base by means of a cross bar 58, the ends of which are deflected downwardly so as to extend underneath ribs on the base.

The feed bar 46 is raised and lowered by means of an eccentric 59 mounted on the main shaft 15. This eccentric is located so as to engage the feed bar at the forward end thereof and substantially beneath the feed dog carried by the feed bar. The material is held on the work support and in cooperative relation to the feed dog by means of a presser foot 60. The presser foot 60 is carried by a presser bar 61. This presser bar 61 is mounted in a sleeve bearing 62 carried by the needle head. This sleeve bearing extends up into the needle head and projects below the lower face thereof. The presser bar terminates a short distance above the lower end of the needle head, and mounted on the upper end of the presser bar is a bracket 63. This bracket has a rearwardly projecting arm 64

which extends through a slot in the wall of the needle head so as to prevent the presser bar from oscillating in its supporting bearing. A leaf spring 65 bears on the bracket 5 63. This leaf spring is supported on a lug 66 at its rear end and an adjustable screw 67 engages the spring intermediate its ends and places the presser bar under variable spring tension. The presser bar is lifted by a hand 10 lever 68 which is pivoted at 69 to the needle head, and is adapted to engage a stud 70 carried by the bracket 64 and projecting through a slot in the front cover plate of the needle head.

15 Mounted on the needle bar is a thread eye 71 which extends through a slot 72 in the front wall of the needle head. Mounted on the overhanging arm is a thread guide 73 which may be adjusted vertically. Also 20 mounted on the overhanging arm is a thread guide 74 which may be adjusted angularly. Also mounted on the hollow standard is a thread guide 75 and tension disks 76. This is for the needle thread which passes through 25 the disks and through these thread guides and then into the needle. The looper thread passes the tensions 77, thence through thread guides 78 and 79. From the thread guide 79, the looper thread passes through a groove 30 80 formed in the removable cover plate 81 and thence into a slot 82 beneath the cloth plate 2. After passing through the slot, the looper thread passes to a thread guide 83, thence through a thread guide 84 to a thread 35 guide 85 and thence to the looper. The thread guide 84 is carried by the link 34 and as the link moves back and forth, this thread guide will move back and forth, and thus control the looper thread. The reservoir may be 40 plied with oil through oil ports 86 in front of the machine, or oil ports 87 at the rear of the machine. The presser foot is provided with a finger guard 88.

It will be apparent from the above that we 45 have provided a sewing machine wherein the actuating parts are housed within the hollow frame which is enclosed so as to provide an oil reservoir, and the splashing of the oil through the rotating of the eccentric parts 50 dipping into the same, thoroughly lubricates all of the parts within the hollow frame. The needle, the looper and the feed dog are well protected from the lubricating oil by the cross partition in the hollow frame. It will 55 further be noted that the presser bar is directly above the eccentric which raises and lowers the feed dog. This avoids strain on the operating parts. The needle bar, as a consequence, is set well forward of the main 60 actuating shaft. The needle lever extends in an inclined direction from front to rear relative to the axis of the actuating shaft, so that the eccentric strap which operates the needle lever is connected to the needle lever 65 in a line directly above the actuating shaft.

The needle lever is a straight line lever, and the manner of supporting and actuating the same, form no part of the present invention, except as to the arrangement of the lever within the hollow frame. The needle lever construction is shown, described and claimed in our Patent No. 1,737,395, granted November 26, 1929.

70 It will be noted that the parts of the machine are comparatively simple in construction and arrangement, and are all positive in their actuation. This, together with the system of lubricating described, contribute to a very high speed machine.

75 It is obvious that minor changes in the details of construction and the arrangement of the parts may be made without departing from the spirit of the invention as set forth in the appended claims.

80 Having thus described the invention, what we claim as new and desire to secure by Letters-Patent, is—

85 1. The combination with a sewing machine frame including a hollow enclosed base, a hollow standard connected to the base, a hollow overhanging arm carried by the standard and having a needle head at its outer end; of a needle bar in said head, an actuating lever mounted in said arm and standard for said needle bar, an actuating shaft extending into said hollow base, an eccentric member on said shaft, means operated by said eccentric member for vibrating said lever, said base serving as a reservoir for the lubricating oil whereby the oil is 90 splashed by said eccentric member and thrown in the form of a mist into said hollow standard and hollow arm, said means for actuating the lever supporting a splash plate 95 adjacent the upper end of the standard.

100 2. The combination with a sewing machine frame including a hollow enclosed base, a hollow standard connected to the base, a hollow overhanging arm carried by the standard and having a hollow needle head at its outer end; of a needle bar in said head, an actuating lever mounted in said arm and standard for said needle bar, an actuating shaft extending into said hollow base, an eccentric member on 105

110 said shaft in said hollow base, means operated by said eccentric member for vibrating said lever, said base serving as a reservoir for the lubricating oil whereby the oil is splashed by said eccentric member and thrown in the form of a mist into said hollow standard, hollow arm and hollow head, said means for actuating the lever supporting a 115

120 splash plate adjacent the upper end of the standard, said needle head having oil pads at the lower portion thereof for lubricating the needle bar and for preventing the oil from escaping at the lower part of the needle head.

125 3. The combination with a sewing machine frame including a hollow enclosed base, a 130

- hollow standard connected to the base, a hollow overhanging arm carried by the standard and having a hollow needle head at its outer end; of a needle bar in said head, an actuating lever mounted in said arm and standard for said needle bar, an actuating shaft extending into said hollow base, an eccentric member on said shaft in said hollow base, means operated by said eccentric member for vibrating said lever, said base serving as a reservoir for the lubricating oil whereby the oil is splashed by said eccentric member and thrown in the form of a mist into said hollow standard, hollow arm and hollow head, said means for actuating the lever supporting a splash plate adjacent the upper end of the standard, said hollow arm having the floor thereof inclined toward the hollow standard for draining the oil accumulating in the arm back into the reservoir.
4. The combination with a sewing machine frame including a hollow enclosed base, a hollow standard connected to the base, a hollow overhanging arm carried by the standard and having a hollow needle head at its outer end; of a needle bar in said head, an actuating lever mounted in said arm and standard for said needle bar, an actuating shaft extending into said hollow base, an eccentric member on said shaft in said hollow base, means operated by said eccentric member for vibrating said lever, said base serving as a reservoir for the lubricating oil whereby the oil is splashed by said eccentric member and thrown in the form of a mist into said hollow standard, hollow arm and hollow head, said means for actuating the lever supporting a splash plate adjacent the upper end of the standard, said needle head having oil pads at the lower portion thereof for lubricating the needle bar and for preventing the oil from escaping at the lower part of the needle head, the floor of said hollow arm being provided with a trough inclining downward toward the standard for draining the oil back into the standard.
5. The combination with a sewing machine frame including a hollow enclosed base, a partition dividing said hollow base into an oil reservoir, and a chamber for the looper and feed bar, a hollow standard connected to said base, a hollow overhanging arm connected to said standard and a hollow needle head carried at the outer end of said standard; of a needle bar reciprocating in said needle head, an actuating shaft extending through said hollow base, actuating means located within the base, standard and arm for reciprocating the needle bar, and for splashing the lubricating oil contained within the oil reservoir, a looper cooperating with the needle, a looper carrier, a support for the looper carrier including a shaft extending through the partition into the oil reservoir, means within the oil reservoir for operating the shaft, a link connected to the looper carrier for oscillating the carrier, said link extending through an opening in the wall into the oil reservoir, and a rock frame in said oil reservoir for moving said link endwise for oscillating the looper carrier.
6. The combination with a sewing machine frame including a hollow enclosed base, a partition dividing said hollow base into an oil reservoir and a chamber for the looper and feed bar, a hollow standard connected to said base, a hollow overhanging arm connected to said standard; of a needle bar reciprocating in said needle head, an actuating shaft extending through said hollow base, actuating means located within the base, standard and arm for reciprocating the needle bar, and for splashing the lubricating oil contained within the oil reservoir, a looper cooperating with the needle, a looper carrier, a support for the looper carrier including a shaft extending through the partition into the oil reservoir, means within the oil reservoir for operating the shaft, a link connected to the looper carrier for oscillating the carrier, said link extending through an opening in the wall into the oil reservoir, a rock frame in said oil reservoir for moving said link endwise for oscillating the looper carrier, a yielding diaphragm for closing the opening about the link in the partition so as to permit said link to move laterally during its endwise movements, and means for supporting said diaphragm.
7. The combination with a sewing machine frame including a hollow enclosed base, a hollow standard connected to the base, a hollow overhanging arm carried by the standard and having a hollow needle head at its outer end, a needle bar in said head, an actuating lever mounted in said arm and standard for said needle bar, an actuating shaft extending into said hollow base, an eccentric member on said shaft in said hollow base, means operated by said eccentric member for actuating said lever, said base serving as a reservoir for the lubricating oil, whereby the oil is splashed by said eccentric member and thrown in the form of a mist into said hollow standard, hollow arm, and hollow head for lubricating the actuated parts therein, said hollow arm having the front end thereof inclined toward the hollow standard for draining the oil accumulating in the arm and hollow needle head back into the reservoir.
- In testimony whereof, we affix our signatures.
- CHARLES S. THOMPSON. 125
WILLIAM B. LONG.
